UNITED STATES PATENT OFFICE.

EARL M. WITHERELL, OF DULUTH, MINNESOTA.

SINKER MECHANISM FOR FORMING OPENWORK KNITTING.

1,413,951.

Specification of Letters Patent. Patented Apr. 25, 1922.

Application filed March 28, 1921. Serial No. 456,056.

To all whom it may concern:

Be it known that I, EARL M. WITHERELL, a citizen of the United States, residing at Duluth, in the county of St. Louis and State 5 of Minnesota, have invented certain new and useful Improvements in Sinker Mechanism for Forming Openwork Knitting, of which the following is a specification, reference being had therein to the accompanying 10 drawing.

This invention relates to knitting machines which are equipped with web holders or sinkers for engagement with a web intermediate the wales thereof and has special 15 reference to an auxiliary web holder or sinker for such machines.

The principal object of the invention is to provide such auxiliary sinkers wherein to produce what is referred to in the art as 20 "mock drop stitching," being in reality an abnormal space intermediate of certain groups of wales such as are common in the ribbed portions of hosiery and the like.

Other objects and advantages of the invention will appear in the further description 25 thereof.

Referring to the accompanying drawing forming part of this application and in which like reference characters indicate like 30 parts:

Figure 1 is a side elevation of one of the auxiliary sinkers;

Figure 2 is a similar view of a common web holder or sinker;

Figure 3 is a transverse sectional view of 35 the upper fragmental portion of the needle cylinder and sinker head of a circular knitting machine as equipped with my improved auxiliary sinkers and mechanism for operating same;

Figure 4 is a plan view of a fragmental portion of the sinker head, and

Figure 5 is an enlarged plan view of one 45 of the common sinkers in its upright position and one of the auxiliary sinkers in cooperative relation therewith.

1 represents the needle cylinder of the machine about the upper end of which is the 50 annularly shaped sinker ring or web holder ring 2 and in which are formed the radially disposed spaced slots 3 in which the ordinary web holders or sinkers 4 reciprocate. 5 represents the vertically disposed needles which 55 are carried in the usual manner in spaced slots about the circumferential edge of the cylinder 1 and which does not form an es-

sential part of my present invention. 6 represents the annularly shaped cam carrier which is mounted upon the ring 2 and into the cam recess 7 of which upon the under 60 side thereof project the butts 8 of the sinkers.

In order to incorporate my present invention in a machine of this character the width or thickness of the common sinkers 4 at the point in the garment where the drop stitch 65 is to occur is reduced by approximately one half and one of the auxiliary sinkers 9 is installed in close juxtaposition with the thus thinned sinker, they being independently reciprocable, but operated in the same slot. 70 The auxiliary sinker 9 is of the same general shape as the sinker 4 except that the butt carrying shank is considerably longer so that the butts may operate in an independent cam race from that in which the butts of the common sinkers operate, and I prefer to make 75 the web receiving notch 10 of the auxiliary sinker slightly higher than the notch 11 of the common sinker so that when the web is carried inwardly by the auxiliary sinker it 80 will be somewhat slightly raised to further increase its abnormality when acted upon by said auxiliary sinker.

Upon the under side of the cam head 6 adjacent the circumferential edge thereof and 85 in a suitably formed recess are two horizontally operated cams 12 and 13, they being pivotally mounted on a common pin indicated at 14 and are intermittently operative within the cam race or path of the butts 90 8 of the auxiliary sinkers so as to engage said butts at a predetermined point in the rotation of the machine. The cam 13 is somewhat shorter than the cam 12 and they are controlled by vertically disposed L-shaped 95 rocker arms 15 and 16 respectively, the arms 15 and 16 being pivotally mounted as at 17 in a suitable bracket 18 attached to the cam carrying ring 6 and are automatically operated by their cooperative portions 100 of the machine not shown, but common in the art, so that the cams 12 and 13 are forced inwardly at the proper moment to similarly actuate the sinkers 9 at the proper predetermined time during the rotation of the needle 105 cylinder.

I have shown the butts of certain of the auxiliary sinkers as being higher than certain others of said sinkers which is necessary for the independent operation of such 110 groups when, for example, the first portion of a hose is knitted wherein only a part

thereof is formed with the mock stitch and the other part plain knitted, thus requiring the independent control of the different sets of auxiliary sinkers which is accomplished by the double cams 12 and 13 above described.

Now the object of the auxiliary sinkers being that of abnormally pulling or sinking the web of the fabric intermediate of the 10 wales, said sinkers are so arranged in connection with their controlling cams as to be thrust inwardly the proper distance beyond the limits of the common sinkers 4 and thus abnormally carry and hold the web in such 15 position during the subsequent forming of the stitch, which results in the desired increased space intermediate of the wales of the fabric at such predetermined points, and it is evident that these auxiliary sinkers may 20 be spaced within the head of the needle cylinder as required to produce the desired spacing of the mock drop stitch.

The auxiliary sinkers may thus operate wholly independently of their adjacent common sinkers 4 and vice versa so that the 25 normal operation of the knitting machine is in no way interfered with.

An auxiliary sinker may be used in combination with all of the common sinkers in 30 a knitting machine and thus produce a

loosely woven fabric if desired, as, for example, when an elastic thread is incorporated within a portion of a garment.

Having thus described my invention, what I claim and desire to secure by Letters 35 Patent, is:

1. The combination with a knitting machine having a plurality of spaced reciprocable sinkers slideable within slots in the sinker ring of said machine, of auxiliary web 40 sinkers one of which may be positioned within any desired slot and slidably engaging the sinker within said slot.

2. The combination with a knitting machine having a plurality of spaced reciprocable sinkers slideable within slots in the sinker ring of said machine, of auxiliary web sinkers one of which may be positioned within any desired slot slidably engaging the sinker within said slot, and means for 45 optionally independently operating the auxiliary sinkers in excess of the other sinkers for the purpose described.

In testimony whereof I hereunto affix my signature in the presence of two witnesses.

EARL M. WITHERELL.
